UNITED STATES PATENT OFFICE.

JOSEPH E. STRAKER, JR., OF ATTLEBORO, MASSACHUSETTS, ASSIGNOR TO THE WATSON AND NEWELL COMPANY, A CORPORATION OF RHODE ISLAND.

DESIGN FOR A HANDLE FOR SPOONS OR SIMILAR ARTICLES.

SPECIFICATION forming part of Design No. 36,121, dated October 28, 1902.

Application filed August 5, 1902. Serial No. 118,507. Term of patent 7 years.

To all whom it may concern:

Be it known that I, JOSEPH E. STRAKER, Jr., a citizen of the United States, residing at 21 Third street, in the town of Attleboro, in the county of Bristol and State of Massachusetts, have invented a new, original, and ornamental Design for the Handle of a Spoon or Similar Article, of which the following is a specification, reference being had to the accompanying drawings, forming part thereof.

On the drawings, Figure 1 is a view of the obverse side of the handle, showing my new design; and Fig. 2 the reverse side of the same.

The leading feature of my design consists in the peculiar and novel outline and ornamentation of the handle, consisting of the head A, a swell portion B, (inclosing the plain panel C,) and the shank D and ornamented 20 with an artistic arrangement in relief of the stems, leaves, buds, and full-blown blossom of the poppy-plant. Both the obverse and the reverse sides of the handle have for a bead the stem E, composed of the heavy raised 25 outer portion f and the narrow inner line g, which stem curves outward at the lower end of the shank D and terminates in the scrolls 3. On the obverse side, Fig. 1, between the scrolls 3 and extending in a convex curve 30 across the base of the handle is the leaf 4, beneath which disappears the upward-curving stem 5, reappearing above it in the form of an upturned bud 6, surmounted by the foliage 7, which extends upward into the narrow 35 part of the shank D. About midway of the handle and at the base of the panel C the leaves 8, springing from the inner edges of the bead E, cross each other in an upward direction and overlap the bead on the opposite side. Near the top of the swell portion B the bead E terminates in foliage, of which the leaves 9 curve upward and inward, forming an arch over the panel C, the leaves 10 face

inward, so that their backs form the concave edges of the handle between the head A and the swell portion B, and the leaf 11 extends in an inward and upward direction, disappearing beneath flower-petals in the head A. The stems 12 appear from beneath the leaf 11 and, passing under the upper portions of the leaves 10, terminate in the buds 13, to whose irregular contour conforms the outer and part of the upper edge of the head A. Between the buds 13 lies a large full-blown poppy-blossom 45 14, facing downward, with its petals partially overlapping the one and disappearing beneath the other of the buds 13 and beneath which disappears said leaf 11. Surmounting the blossom is the stem 15, which curves upward and downward, disappearing behind the blossom and forming the apex of the handle. On the reverse side, Fig. 2, just above the swell portion B, the bead E terminates in the inward-folded leaves 4, whose backs form the side and a portion of the top edge of the head 50 A. The remaining portion of the top edge of the head A conforms to the outline of the small buds 5 and the semicircular apex 6, which is ornamented with the downward-pointing leaf 7. The small buds 5 surmount 55 the stems 8, which extend in compound curves down into the panel C, passing on one side beneath the upper part of the leaf 4.

Having described my invention, what I claim as new, and desire to secure by Letters 75 Patent, is—

The ornamental design for a handle for a spoon or similar article substantially as herein shown and described.

In testimony whereof I have affixed my signature in presence of two witnesses.

JOSEPH E. STRAKER, JR.
